CLAIM

The ornamental design for a padded chair, as shown
and described.

DESCRIPTION

FIG. 1 is a left side front top perspective view of a
padded chair showing my new design, the right side
being a mirror image of the side shown;

FIG. 2 is a top plan view thereof;

FIG. 3 is a top front perspective view thereof;

FIG. 4 is a perspective view thereof from the rear; and,
FIG. 5 is a perspective view from the rear and bottom
thereof.

FIG. 1

FIG. 2

FIG. 3

FIG. 4

FIG. 5
